UNITED STATES PATENT OFFICE.

LYMAN B. LANGWORTHY, OF CHICAGO, ILLINOIS, ASSIGNOR TO CHICAGO TITLE & TRUST CO., TRUSTEE, OF CHICAGO, ILLINOIS, A CORPORATION OF ILLINOIS.

CONCRETE WALL AND METHOD OF MAKING SAME.

Application filed March 2, 1920. Serial No. 362,881.

To all whom it may concern:

Be it known that I, LYMAN B. LANGWORTHY, a citizen of the United States of America, and a resident of Chicago, county of Cook, and State of Illinois, have invented certain new and useful Improvements in Concrete Wall and Methods of Making Same, of which the following is a specification.

This invention relates mainly to the construction of foundations, walls, caissons, dikes, jetties, breakwaters, and the like, especially where great strength and safe foundations are required. The main objects of the invention are to provide an improved form of piles, wall units or sections adapted for sinking into place in the manner of piles; to make provision therein for applying a hydraulic earth removing jet; to provide a reinforced concrete pile of improved form adapted for ready sinking; and to provide for injecting through the several piles material to form a concrete footing for the wall after the piles are in place.

An illustrative embodiment of this invention is shown in the accompanying drawings, in which—

Fig. 1 is a front elevation of a reinforced concrete wall composed of similar internal jetty piles, one of the piles being in section to show the reinforcing.

Fig. 2 shows an edgewise view of said wall at one of the joints where adjacent piles abut.

Fig. 3 is a section at 3—3 on Fig. 1.

Fig. 4 is a front elevation of a wall composed of alternately disposed piles and panels.

Fig. 5 is a section at 5—5 on Fig. 4 where adjacent piles abut.

Fig. 6 is similar to Fig. 5 except that the panel is guided on both front and back by pile flanges.

Fig. 7 is an enlarged vertical sectional detail of the spud and associated parts on the line 7—7 of Figure 1.

In the construction shown in the drawings, reference being had to Figs. 4 and 5, the wall units 1 and 2 are all of reinforced concrete and each is provided with one or more water tubes or jet pipes 3. Said tubes 3 are arranged lengthwise of the piles 1 and panels 2 and project at the ends as at 4 and 5. Water may be supplied thereto under pressure as by connecting same at 4.

As thus used, the water is forcibly ejected at the lower ends 5 whereby the earth is hydraulically loosened and more or less removed from the path of the downwardly moving part. Thus the body 1 or 2 may be readily sunk into place.

The piles 1 are provided with flanges or rabbets 6 on their front corners to secure the interposed panels 2 against the pressure of the material held back by the wall. Rear flanges 6' are also desirable in some instances.

The abutting edges of the wall members are longitudinally grooved in mutual registry nearly to the lower ends to provide a closed tubular chamber or cup 7 to receive a locking key of bonding material 8, the bottom of said cup being indicated at 7'.

Each pile 1 is provided with reinforcing means 9, and each panel 2 contains a reinforcement 10. The edges of reinforcements 9 and 10 project somewhat into the corresponding cup grooves 11 and 12 respectively, to engage with or become set in the body of the key 8, as explained in my copending application Serial No. 362,882, filed of even date herewith. Each wall member or unit 1 and 2 is provided with a lifting staple 13 or the like set in its upper end, as shown in Figs. 1, 2 and 4.

In case the wall is to be constructed of piles alone, as shown in Figs. 1 and 3, the piles 14 may be formed substantially as in Fig. 4 except that the guide flanges are omitted. The reinforcement 15 may also be of a different design, but the edges thereof extend into the cups 16 substantially as in the first described form of wall. A footing 8' is forced down under the wall through the jet pipes 3 and apertures 11 and 12 after the piles and panels are in place.

In each case, the tubing for the jet pipes 3 extends well below the tip of the pile or panel and is protected part way by a cylindrical sleeve of reinforced concrete 17 contiguous with the lower end of the wall member. The upper end of each pile tube and the middle tube of each panel may be so positioned and related to the staple 13 as to be protected thereby from mechanical injury. The lower ends of spuds 17 and tubes 3 are about flush, though the jet pipe may project somewhat beyond the spud. The lower end of each pile is protected by a metal shoe

18 formed with a wedge shaped penetrating point or edge and including a projecting armor for the spud and jet pipe.

In claiming my invention I use the word 5 pile in a broad sense including wall members or units which may be in the form of either piles (such for instance as 1) or panel (illustrated by 2).

Although but two specific embodiments 10 of this invention are herein shown and described, it is to be understood that some of the details of the construction shown may be altered or omitted without departing

from the spirit of this invention as defined by the following claim.

I claim:

A concrete pile having a jet pipe disposed therein and projecting therefrom at the lower end of said pile, a concrete spud surrounding the projecting end of said pipe, 20 and a beveled metallic shoe member on said end to protect the said pipe, spud and pile.

Signed at Chicago, this 5th day of February, 1920.

LYMAN B. LANGWORTHY.
